GARMENT DRYER APPARATUS

Adolph F. Graf von Soden, 3909 Riviera Drive, Pacific Beach, San Diego, Calif., and Louise Teter, 177 Orlando, El Cajon, Calif.

Filed Oct. 25, 1963, Ser. No. 318,980
1 Claim. (Cl. 223—63)

This invention relates to garment stretchers and dryers and more particularly to a self-adjustable and extendable apparatus of the dismountable type that may be easily housed in a small package.

Manifestly, an object of the invention is to provide a combined stretcher and dryer apparatus having a set of interchangeable edge plate member means, wherein, each being provided with a longitudinally defined edge, said plate member means having a uniform cross-section forming sections that may be longitudinally extended to any desired length when connecting the ends thereof, and also, having suitable resilient means associated therewith for spreading the extendably assembled ends for holding same taut and in position when drying and for creasing the garment, said garment being of the particular "capri" type that is worn by women.

Accordingly, an object of the invention is to provide a combined stretcher and dryer apparatus having a set of longitudinally extendable and detachable edge plate member means, each member means having a longitudinally defined edge, each end of which being provided with a suitable interlocking means adapted for holding said edge plate member means in an extended and rigid position.

Another object of the invention is to provide each of said edge plate member means with a longitudinal ridge which is of suitable shape and construction and adapted for securing an even crease in a garment when stretching and drying same.

A further object of the invention is to provide each of said edge plate member means with a detachable and removable blade edge for securing a sharp crease when in use, and also, having a removable and interchangeable resilient spring means associated therewith for spreading the ends of said edge plate member means, said spring means having a loop adapted for hanging said stretcher together with the garment when drying same.

Another object of the invention is to provide said stretching and drying garment apparatus with interchangeable parts, so that same may be placed and positioned endwardly when in operation, to be convenient in use, easily installed in a working position and easily disconnected therefrom, economical in operation and manufacture, relatively simple and of general superiority and serviceability.

The invention also comprises novel details of construction and novel combinations and arrangements of parts, which will more fully appear in the course of the following description.

Reference is now had to the accompanying drawings, in which the similar reference characters denote the same parts.

In the drawing:

FIG. 1 shows a front plan view of the stretcher and dryer apparatus, that is shown in sections assembled endwardly, and showing the ends of the separate edge plate member means secured together by locking plates, and also showing the spreading spring means at the ex-

2

tended ends of said stretcher and dryer apparatus when in position.

FIG. 2 shows a vertical side elevational view of one of the edge plate member means provided with locking members in modified form, adapted for securing an endward attachment and combination.

FIG. 3 shows a fragmentary side view of the edge plate member that is shown slightly enlarged, taken from FIG. 2, and showing the position of lock pins at the end thereof.

FIG. 4 shows a sectional end view of the edge plate member, shown without the locking plate and taken on lines 4—4 of the FIG. 3.

FIG. 5 shows a fragmentary vertical and a sectional view of the edge plate member, showing a sliding locking plate in position and taken in the direction of the arrows A—A in FIG. 4.

FIG. 6 shows another vertically sectional and fragmentary view edge plate member shown with a hinged locking plate in place, showing same in a modified form, and also taken in the direction of arrows A—A of FIG. 4.

FIG. 7 shows a fragmentary and a sectionally vertical view of the edge plate member, showing the ends thereof provided with a detachable locking plate when in position showing same in a modified form, and also taken in the direction of the arrows A—A of FIG. 4.

FIG. 8 shows another vertically and fragmentary sectional view of the edge plate member showing the ends thereof provided with a removable and detachable locking plate, showing same in a modified form and also taken in the direction of the arrows A—A of FIG. 4.

FIG. 9 shows a side elevational view of the spring member when in its normal position.

FIG. 10 shows a sectional view of the edge plate member, showing a removable edge section, and showing same in a modified form.

FIG. 11 shows a vertically sectional view of the edge plate member showing hinge bushing in position, and showing same in its modified form.

Describing said invention more in detail in its broader aspects, said invention comprises a pair of longitudinally identical edge plate member means, which are shown in an endwardly combined position that are attachable at the ends for forming same into suitable lengths and generally designated by numerals 2 and 4.

Said longitudinally combined edge plate member means 2 and 4 being the right and left section members respectively, each of which consists of a plurality of longitudinally identical plate sections 2^a, 2^b, 2^c and the 4^a, 4^b and 4^c plate sections respectively, which may be extended endwardly and connected together into any desired length, as in practice may be found to be most desirable and practicable, as shown in dotted lines in FIGS. 1 and 2.

Each longitudinal plate section of said edge plate member means 2 and 4 is provided with a longitudinal slot 6, see FIGS. 4 and 10, for securing a narrow slot shaped cross-section having an open end 8 which is formed by a pair of equilateral side plates 10 and 12, and which are conjoined in an arcuate section 14.

Said conjoined arcuate section 14 is formed into a suitable configuration for securing a longitudinally extending leading or crease edge 18; said crease edge may be substantially an integral part of said arcuate section 14 that extends outwardly at a suitable width therefrom, as shown in FIGS. 1, 3 and 4, or, said arcuate section 14 may be provided with a suitable groove 16 wherein a blade 20 is detachably mounted, as shown in FIG. 10, the purpose of which will be presently described.

Each separate plate section of said combined edge plate member means 2 and 4 is provided with an end section 22 and 24, respectively, each end thereof being adapted for an endward abutting of the respective end of the adjoining plate section when same are arranged in a sectionally and longitudinally extended position, as shown in FIG. 1, and when said apparatus, thus endwardly assembled, is used for the garment stretching and drying operation, and also for providing a longitudinal crease in a drying garment.

Each end section 22 and 24 is provided with a pair of pins of which, the end pins 26 and the inner pins 28 are used for forming a supporting bridge between said pair of side plates 10 and 12 respectively, of which said pins 26 are positioned in close proximity to the ends of said respective end sections, while said pins 28 are disposed away from said pins 26 and are equally spaced in an inwardly extended position, and which are used for supporting the interchangeable locking plates 30 in a hinged position, thus holding and locking said separate ends of said plate sections in a longitudinally extended position, as shown.

The extreme free ends 22^a and 24^a of the respective plate sections 2^a, 4^a and 2^c and 4^c, shown in FIG. 1, are used for engaging and for supporting in place a suitable spreading spring member means 32 disposed one at each end for causing the garment, such as trousers and pants for men, or the "capri" type pants for women, to be stretched and dried.

When said end sections 22 and 24 are assembled and held endwardly together in locked position by means of said locking plates 30, each hinging end 34 of said locking plate is arranged for engaging the inner pin 28, see FIG. 5, the extended body section of said plate having a recess 36 disposed therein for securing a clearance for the end pin 26, while the extended end 38 of said locking plate is provided with a slot 40 adapted for engaging the end pin 26 of the adjoining and abutting end of said end section 22, said locking plate also having a longitudinal end wedge extension 42 for securing a wedge locking effect between said end pin 26 and the slot bottom surface section 6^a of said longitudinal slot 6 of the abutting end section 22, thus locking the respective plate ends together as shown.

As shown in FIG. 1 said locking plates 30 are provided only with two slotted holes 44 which are adapted for receiving the respective end pins 26 at the extending ends of said end sections 22 and 24. The modified locking plates 30^a shown in FIGS. 2 and 6 are adapted for hingedly engaging the inner pins 28 of the end sections 24^a and 24, and each locking plate is also provided with a suitable wedge extension 42 for allowing same to be positioned within said slot 6 and wedged forwardly against the end pin 26 disposed in the abutting end of the plate end 22, as shown in FIG. 5, and thereby locking the respective end sections together, and for holding said edge plate member means 2 and 4 in a longitudinally rigid position when in use.

Said hinging end 34 of said locking plate 30^a is also provided with a suitable cross entry slot 46 which is adapted for a convenient assembly and also for allowing said locking plate 30^a to be swung outwardly and back into said slot 6 when said locking plate is in inoperative or not in used position.

In the FIG. 5, the locking plate 30' shown in modified form, is provided, at one end, with a sliding hinged end 34 having an assembling slot 46 disposed at a pivoting end section 48 that is adapted for engaging only said end pins 26 of the abutting end sections 24 and 22, and which are provided in the endwardly adjoining plate sections 2^a, 2^b and 2^c including 4^a, 4^b and 4^c plate sections as shown in FIG. 1, while the oppositely extended end of said locking plate 30' is provided with an end slot 40' and having a wedge extension 42' adapted for engaging the adjoining end pin 26 of the abutting end section 22 and also for wedging said wedge extension 42' against the

slot surface section 6^a, thereby locking the plate end sections 22 and 24 together and in readiness for use.

A locking plate 30", as shown in modified form in FIG. 7, is provided with an end slot 50 and has a wedge extension 42" disposed at one end and a wedge extension 52 positioned at the opposite end thereof, said wedge extensions 42" and 52 being adapted for engaging each of slot surface sections 6^a of said slot 6 including the respective end pins 26 disposed at the ends of the end sections 22 and 24 of the respective plate sections.

10 The modification of said locking plate 30"" shown in FIG. 8 comprises a pair of wedging ends 54 and 56 adapted for wedging same between said respective pins 26 disposed at the ends of said end sections 22 and 24 of the abutting plate end sections including the respective slot surfaces 6^a of said slots 6, thereby locking said ends together and also holding said edge plate member means in a longitudinally rigid and extended position when in use.

Said spreading spring member 32, as shown in its normally extended position in FIG. 9, is provided with a 20 pair of spring arms 58 each of which is provided at its respective end with an end loop 60, said spring being adapted for spreading the extended ends of said edge plate member means 2 and 4 as shown in FIG. 1, by allowing said looped ends 60 including said spring arms 58 to slide into said slot 6 and between said slot surface section 6^a and the pins 26 disposed at the end plate sections 22 and 24.

Also, said spring member 32 is provided with a center 30 loop 62 for securing an additional resiliency therein when in use and also for providing means for handling same when said apparatus is used for stretching and drying of the garment and for securing a crease in said garment by means of said edge member 18 or the blade member 20, as hereinbefore described.

While this invention is described with great particularity it will be clear that the same may be modified throughout a wide range.

Accordingly, it is not proposed that this invention be limited to the exact details of construction herein shown on the drawings and described in the specification, and therefore, reservations of the rights in practice are made herein to the end that necessary changes and modifications may be had therein, which may come within the scope of the appended claim.

45 We claim as our invention:

In a garment drying, stretching and creasing apparatus of the class described comprising, a plurality of longitudinally extending edge plate members, an end plate section in each edge plate member and at each end thereof, longitudinal slot having a slot bottom surface section extending longitudinally and at one edge of the entire length of said edge plate member for forming an open end and also securing a pair of side plates therein, a set of pins 50 at each end of each end plate section and passing transversely through said open end and said pair of side plates, said pins being in close proximity to said slot bottom surface section of said longitudinal slot securing a bridge therefor; said set of pins consisting of the endwardly positioned end pins disposed at each end of said end plate section and also the inner pins arranged in an equally spaced position from said end pins and being further from the ends of said end plate section; the combination of, a locking plate, a hinging end in said locking plate for pivotally mounting same upon one of said pins and at one end of said end plate section and disposed within said longitudinal slot for enclosing said locking plate therein, a wedge extension at the extended end of said locking plate for engaging said longitudinal slot of the abutted end in the adjoining end plate section and for wedgingly engaging the slot bottom surface including the respective end pin in said abutting end plate section, and thereby locking a pair of endwardly abutting end plate sections together when disposed adjacently to each 60 other and for holding said plurality of longitudinally ex-

tending edge plate members in a rigid position, and spring member engaging the free ends of the longitudinally assembled edge plate members for spreading said free ends and thereby stretching and creasing a garment when drying same.
